Serial No.

2,519,096

This invention relates to an invalid walker which also serves as a chair designed to assist an invalid in walking. The invalid walker and chair having raised and curved arms and a runner-like base so that it can be pushed along a floor with one knee resting on the seat. Where a person has one leg or foot injured and desires to move about a room, it is not always convenient to use crutches, and in addition where the person is not used to crutches the person frequently tries to move short distances without the crutches and falls. With an invalid walker in the form of a chair as embodied in this invention, the invalid can move about a room and can rest at any point, and in addition will not become over-balanced.

An object of this invention is to provide a chair-like invalid walker which can be used by an invalid for seating or can be used to move about, the invalid walker and chair having raised and curved arms and a runner-like base so that it can be pushed along a floor with one knee resting on the seat. Where a person has one leg or foot injured and desires to move about a room, it is not always convenient to use crutches, and in addition where the person is not used to crutches the person frequently tries to move short distances without the crutches and falls. With an invalid walker in the form of a chair as embodied in this invention, the invalid can move about a room and can rest at any point, and in addition will not become over-balanced.

With the above and other objects in view, my invention consists in the arrangement, combination and details of construction disclosed in the drawings and specification, and then more particularly pointed out in the appended claim.

In the drawing,

Figure 1 is a detail front elevation of an invalid walker and chair constructed according to an embodiment of this invention,

Figure 2 is a detail side elevation of the invalid walker and chair,

Figure 3 is a sectional view taken on the line 3—3 of Figure 1.

Figure 4 is a detail side elevation of a modified form of this invention,

Figure 5 is a detail front elevation of the invalid walker and chair shown in Figure 4,

Figure 6 is a sectional view taken on the line 6—6 of Figure 4.

Referring to the drawing, the numeral 10 designates generally a frame of the invalid walker which is formed of a pair of spaced parallel horizontal seat supporting members 11 which are of tubular construction. The seat supporting members 11 extend from front to back at the sides of the frame and chair have extending downwardly at right angles or perpendicularly from the forward ends thereof vertical spaced parallel tubular legs 12 and the legs 12 have extending at right angles horizontally and rearwardly from the lower ends thereof spaced parallel base or runner members 13 in vertical alignment with and beneath members 11.

The base or runner members 13 at their rear ends are formed with upturned extensions 14 terminating beneath and in vertical alignment

with the rear ends of the members 11 and the extensions 14 of the base or runner members 13 are connected together by a transverse horizontal upwardly bowed bight portion or connecting member 15 which may be integral with the extensions 14. The rear ends of the seat supporting members 11 have extending at right angles vertically upward therefrom spaced parallel back forming members 16 spaced rearwardly from and parallel to legs 12 and the two back forming members 16 at their upper ends are connected together by a longitudinally curved or arcuate horizontal transverse connecting member or bar 17 forwardly convexed or bowed integral bight portion which forms a practical hand hold or handle bar to facilitate and control the sliding movement and direction of sliding of the device when in use. The connecting member or bar 17 extends forwardly in the center over and overlies the rear portion of a padded seat 18 which is secured by fastening members 19 to the seat supporting members 11 so that bar 17 extends in front of members 16 and the rear edge of the seat and over the latter and the seat 18 projects out in front of the members 11 and 13 and legs 12 as shown to prevent the knees or legs striking the latter. This seat is preferably only about 10 inches square and heavily padded to protect the knee.

Referring now to Figures 4 to 6, there is disclosed a modified form of this invention which includes a frame 10a similar in every respect to frame 10, with the exception that the upper ends of the back forming members 16a are connected together by a longitudinally curved or arcuate horizontal transverse rearwardly convexed or bowed connecting member 20 which has the concave side thereof foremost and extends rearwardly from the seat or pad 18a. The connecting member 20 also includes a pair of outwardly extending handles 21 which may be formed integral with the connecting member 20 and project forwardly and outwardly of and beyond the members 16a and rear edge and sides of the padded seat or knee pad 18a to form a hand hold or handle bar to likewise facilitate and control the sliding movement and direction of sliding of the device when in use.

In the use of this invalid walker and chair, the padded seat or knee pad 18 may be used in the normal manner by an invalid who may have an injury to one leg. When the invalid desires to stand up and move, the invalid may stand on the uninjured leg and may engage the knee pad or padded seat 18 with the knee of the

INVALID WALKER

Forrest Additon, Flowery Branch, Ga.

Application January 13, 1947, Serial No. 721,853

1 Claim. (Cl. 155—22)

1

This invention relates to an invalid walker which also serves as a chair designed to assist an invalid in walking.

An object of this invention is to provide a chair-like invalid walker which can be used by an invalid for seating or can be used to move about, the invalid walker and chair having raised and curved arms and a runner-like base so that it can be pushed along a floor with one knee resting on the seat. Where a person has one leg or foot injured and desires to move about a room, it is not always convenient to use crutches, and in addition where the person is not used to crutches the person frequently tries to move short distances without the crutches and falls. With an invalid walker in the form of a chair as embodied in this invention, the invalid can move about a room and can rest at any point, and in addition will not become over-balanced.

With the above and other objects in view, my invention consists in the arrangement, combination and details of construction disclosed in the drawings and specification, and then more particularly pointed out in the appended claim.

In the drawing,

Figure 1 is a detail front elevation of an invalid walker and chair constructed according to an embodiment of this invention,

Figure 2 is a detail side elevation of the invalid walker and chair,

Figure 3 is a sectional view taken on the line 3—3 of Figure 1.

Figure 4 is a detail side elevation of a modified form of this invention,

Figure 5 is a detail front elevation of the invalid walker and chair shown in Figure 4,

Figure 6 is a sectional view taken on the line 6—6 of Figure 4.

Referring to the drawing, the numeral 10 designates generally a frame of the invalid walker which is formed of a pair of spaced parallel horizontal seat supporting members 11 which are of tubular construction. The seat supporting members 11 extend from front to back at the sides of the frame and chair have extending downwardly at right angles or perpendicularly from the forward ends thereof vertical spaced parallel tubular legs 12 and the legs 12 have extending at right angles horizontally and rearwardly from the lower ends thereof spaced parallel base or runner members 13 in vertical alignment with and beneath members 11.

The base or runner members 13 at their rear ends are formed with upturned extensions 14 terminating beneath and in vertical alignment

other leg. The forwardly extending connecting member 17 or the rearwardly extending connecting member 20 and ends 21 constitute a handle which may be grasped by one or both hands of the invalid and the device may then be pushed over the floor, the runners 13 readily sliding over the floor. In this manner the invalid or person with an injured foot can easily and safely propel himself or herself around without danger of falling as often happens when using crutches, rest 10 at any desired point and can readily move from one point to another without the use of crutches.

By forming the frame of the invalid walker and chair out of tubular material or metal, the frame can be made as a single tubular unit and 15 the frame can be made out of relatively light-weight, strong, resilient material. In this manner the invalid walker and chair can be readily pushed by the invalid along the surface of the floor when it is desired to move from one point 20 to another.

I do not mean to confine myself to the exact details of construction herein disclosed, but claim all variations falling within the purview of the appended claims.

What I claim is:

An invalid walker and seat comprising a frame formed of a bar having a pair of horizontal seat supporting members; a pair of horizontal bottom members parallel with and beneath said seat supporting members; a pair of vertical front leg members integral with the forward ends of said

seat supporting and bottom members, said bottom members having upturned rear portions with a bight portion connecting the same, a pair of back forming members extending upwardly from the rear ends of said seat supporting members, a connecting bar between the upper ends of said back forming members and forming a handle bar, and a seat secured to said seat supporting members and projecting forwardly of the leg members, said bar projecting forwardly a substantial distance over the seat and adapted to be gripped for sliding the device about the floor on the bottom members with one knee resting on the seat and one foot on the floor.
